UNITED STATES PATENT OFFICE.

HOYTE C. HADSTATE AND STEPHEN J. MARTIN, OF DETROIT, MICHIGAN,
ASSIGNORS, BY DIRECT AND MESNE ASSIGNMENTS, TO CARTER &
COMPANY, LIMITED, OF NIAGARA FALLS, NEW YORK.

NUMBERING-MACHINE.

SPECIFICATION forming part of Letters Patent No. 443,517, dated December 30, 1890.

Application filed April 19, 1889. Serial No. 307,792. (No model.)

To all whom it may concern:

Be it known that we, HOYTE C. HADSTATE and STEPHEN J. MARTIN, citizens of the United States, residing at Detroit, in the county of Wayne and State of Michigan, have invented 5 a new and useful Improvement in Numbering-Machines, of which the following is a specification.

This invention relates to an improvement 10 in numbering-machines, and has for its object the production of a machine by which consecutive numbers may be printed upon separate sheets of paper succeeding one another or upon the successive parts of a long 15 roll of paper as the sheets or rolls are fed under the machine.

Our device is especially useful in the preparation of what are known as "duplicating sale-slips," where it is desired to produce a 20 number of blanks duplicates in every thing except the number imprinted on them, and which after being printed are to be bound into book form or pad form with the consecutive sheets numbered in order from one to the 25 highest number.

Our device is used in connection with the printing-cylinder on which are mounted the type-forms for printing the required blank, and it is used in this connection in order that 30 the operation of printing the blank and printing the number may be accomplished at the same time, though the device will accomplish its own work whether used alone or used in connection with the printing-cylinder spoken of.

The figures show a device arranged to correspond to a printing-cylinder on which there are mounted five forms of type arranged to print five blanks with each revolution of the 40 printing-cylinder, which our device will number consecutively from one to five, and the following five blanks printed by the printing-cylinder will be numbered from six to ten, and the sequence of numbers will continue 45 until one hundred blanks have been printed and numbered, when the numbering-machine will begin at one again; but the cycle of notation can be changed by changing the number of parts and the number of teeth in the

gear-wheels without in any way deviating 50 from the principle of our device.

Figure 1 shows a side elevation. Fig. 2 shows a top view of the wheel-case A with the wheel-driving gear B C mounted thereon. A portion of the top of case A is broken away 55 in Fig. 2 to show the internal moving-gear actuating the several figure-wheels. Fig. 3 shows the cam K of Fig. 1, by which the driving mechanism of the type-wheels is actuated.

S is the main shaft, mounted upon the frame 60 of the printing-press and rotating in equal time with the printing-cylinder with which our device is to register.

K is a cam fixed to the frame-work of the printing-press. It consists of a circular guide 65 and locking ring mounted so that through the most of its course it is concentric with the shaft S and lies in a plane parallel to the plane of rotation of the wheel-case A. At one part k the ring-cam K is broken, and one 70 end is bent slightly inward and the other slightly outward.

On the face of the wheel-case A is mounted a spur-wheel B, of which the spurs engage with the cam K, and the wheel B is held fixed 75 in its mountings during almost the entire revolution of the wheel-case A; but at the point where the cam K is broken the wheel B is compelled to make a movement on its axis. This movement is that which is due to the 80 forcing of one cog of the wheel B from one side to the other of the circular ring K through the opening k. Concentric with the spur-wheel B is a miter-wheel E, which meshes into a miter-wheel C, mounted upon the spindle of one of the figure-wheels W. 85

Within the wheel-case A are a number of figure-wheels W W W W W. Each of the figure-wheels W is so mounted that a small portion of its periphery extends out through 90 the side of the wheel-case A, and each of the figure-wheels W has engraved upon its periphery figures or characters, by means of which an imprint can be made. The wheel-case A and the contained figure-wheels W 95 form a type-cylinder somewhat similar to the type-cylinder to a printing-press, except that the type are movable and are arranged to

be moved. Upon each one of the figure-wheels W is a pinion P, meshing into an annular wheel R. That one of the pinions P which is on the same shaft with the miter-wheel C is 5 a driving-pinion and acts to drive the annular wheel R, as the miter-wheel is itself moved by the wheel B and cam K. The revolution of the annular wheel moves each of the other pinions and figure-wheels equally with the 10 driving-pinion and causes the presentation of a new figure at the exposed part of each of the figure-wheels each time a new figure is presented on the figure-wheel connected with the driving-pinion.

15 The number of cogs on the wheel B corresponds with the number of figures on each wheel. The miter-wheels E C have the same number of teeth, and preferably each of them has the same number of teeth as the number 20 of cogs on the wheel B, so that one revolution of the wheel-case A moves the wheel B forward one cog, and this movement causes the figures on the figure-wheel W to move forward one space.

25 The arrangement of the numbers on the figure-wheels is determined by the number of figure-wheels that are employed. Where there are five employed, as is shown in the drawings, the sequence on the first wheel would be 30 1 6 11 16 21, and so on, and on the second wheel would be 2 7 12 17 22, &c. If read around the wheel-case, reading the number that is presented to be printed from the reading would be in consecutive numbers from 1 to 5 and 35 at the next revolution of the wheel-case A the reading would be in consecutive numbers from 6 to 10.

Having thus described our invention, what we claim as novel, and desire to have secured 40 to us by Letters Patent, is—

1. The combination of a wheel with printing-figures engraved on the periphery thereof, the described locking guide-ring and cam,

and a spur-wheel intermeshing with said guide-ring and with a pinion on the shaft of 45 the said engraved wheel, substantially as and for the purpose described.

2. A consecutive-number-printing machine consisting of a rotating wheel-case in which are contained a number of printing-wheels, 50 each movable upon its own axis and all connected, as described, to a spur-gear meshing into a disk-cam.

3. A consecutive-number-printing machine comprising a rotary-wheel case, a plurality of 55 printing-wheels pivoted to and distributed around the periphery of said case and protruding with their peripheries through the periphery of the case and each of said printing-wheels provided on its periphery with 60 numbering-types, the numbers of each succeeding wheel being in consecutive progressive order to the numbers of the preceding wheel, pinions fixed to the said printing-wheels, an annular rack meshing with said 65 pinions, a stationary cam arranged with its main portion concentric with the axis of the said wheel-case and terminating at one point with radial deflections, and gears actuated by said cam and transmitting motion to the pinion of one of the printing-wheels, as set forth and shown.

4. A consecutive-numbering machine combining, as described, the rotary carrying-case A, with the numbered wheels W mounted 75 therein, the annular wheel R, pinions P, miter-wheels C and E, spur-wheel B, and disk-cam K, all arranged and interacting, as described, to present consecutive numbers in a position to be printed from as the carrying-case revolves, substantially as described.
